UNITED STATES PATENT OFFICE.

LUTHER P. FRIESTEDT, OF CHICAGO, ILLINOIS.

SHEET-PILING.

SPECIFICATION forming part of Letters Patent No. 734,843, dated July 28, 1903.

Application filed May 21, 1903. Serial No. 158,110. (No model.)

To all whom it may concern:

Be it known that I, LUTHER P. FRIESTEDT, a citizen of the United States, residing at Chicago, in the county of Cook and State of Illinois, have invented certain new and useful Improvements in Sheet-Piling; and I do hereby declare the following to be a full, clear, and exact description of the invention, such as will enable others skilled in the art to which

it appertains to make and use the same.

This invention relates to improvements in metal sheet-piling to be used for various purposes, and has for its object to provide an improved arrangement for retaining the different sections in their joint relation in forming a continuous wall structure.

In the drawings, Figure 1 is a plan of a portion of a wall structure embodying the improved features. Fig. 2 is an elevation in perspective of a single beam-section, showing the back side thereof. Fig. 3 is a similar view, but showing the channel or face side of a beam-section; and Fig. 4 is a view in perspective of a wedge-piece looking at the flat or face side thereof.

The form of rolled beam used is preferably of the channel pattern; but any other form may be employed that will be practical in connection with the improved features to be hereinafter set forth.

The interlocking channel beam-sections entering into the wall structure are arranged in the alternate manner shown in Fig. 1, the section A being set with the flanges 5 turned in one direction and the section B with the flanges 6 turned in the opposite direction, the adjacent flanges of the edgewise-assembled beams interlocking with each other.

The beam-sections have a number of wedge-pieces C secured to the back side and adjacent to one edge thereof. These wedge-pieces will be of the double form and shape best shown in Fig. 4 and are rigidly secured in place, usually by means of rivets, apertures 7 being provided for the insertion of the same. These wedge-pieces are placed upon but one corner edge of each beam and are disposed alternately on opposite sides of the wall, as shown in Fig. 1. Beginning with the first section A the wedges are placed on the free edge, the next wedges are mounted on the joining back edge of section B, and then again on the back

interlocking edge of the succeeding beam-section A, and so on throughout the series of sections, bringing the wedges on the alternating beams into a diagonal relation, so as to locate them first on one side of the wall and then on the other. The wedge-pieces may be placed on both edges of each beam-section when necessary; but the alternate disposition shown is usually sufficient.

The wedge-pieces are flat on the face side 8 and on the back gradually slope from the middle 9 of the greatest diameter to the vanishing ends 10. This double form of wedge is more especially intended for use on temporary work and facilitates the pulling out of the material in condition to be used over again, the double wedge not presenting as great a resistance to the pulling power as the head end of the ordinary wedge would. In structures of a permanent character an ordinary single wedge may be used, the head end of which would be of the form indicated by the rectangular diagrammatic lines in Fig. 4.

When the beam-sections are driven, the pressure on the wedge-surfaces from the earth-walls will be somewhat excessive and the joining edges of the beams constantly held or forced together from each side toward a common center and locked against possible lateral separation.

Angle-irons are employed in connection with the frictional wedging system, as will be next described.

The beam-sections are each provided with an angle-iron D, riveted to the face or channel sides and which prevents any edgewise play thereof. The angle-irons are of a length corresponding to that of the sections and also serve as guides in the operation of assembling and driving. The angle-irons are so disposed that the free flanges 11 contact the beam-flange adjacent to the position of the wedge-pieces in coacting therewith. By this arrangement a locking and guide groove is provided between the free flange of each angle-iron and the adjacent beam-flange alternately on each side of the wall structure, and thus simplifies the construction by being able to retain the beam-sections in their joint relation by using but one angle-iron on each beam and having the wedging-surfaces on but one edge or corner of the respective beam-sec-

tions. If the character of the work is such as to require it, two angle-irons may be used on each beam-section and wedge-pieces mounted on both edges of each section. Ordinarily 5 the single arrangement shown will be sufficient and saves both in material and labor.

Having thus described my invention, what I claim, and desire to secure by Letters Patent, is—

- 10 1. A metal sheet-piling, comprising beam-sections assembled edgewise in forming a solid wall structure, and means carried by the respective sections for receiving a direct lateral pressure on both sides of the structure 15 from contact with the earth walls in retaining the sections in their joint relation during the operation of driving, substantially as set forth.
- 20 2. A metal sheet-piling, comprising beam-sections assembled edgewise in forming a continuous wall structure, and means mounted on each section for exerting an excessive inward pressure on both sides of the wall on a line at right angles thereto when forced into 25 the earth and holding the sections in their edgewise engagement, substantially as set forth.
- 30 3. A metal sheet-piling, comprising channel beam-sections assembled edgewise so that the flanged edges will interlock, a number of angle-irons located on the channel side and adjacent to the edges thereof and rigidly se-

cured in place, and means carried by each beam-section for transmitting the earth pressure on each side of the wall structure in 35 forcing the flanged edges together and holding the same in close parallel engagement, substantially as set forth.

4. In metal sheet-piling, a channel beam-section, and an angle-iron rigidly secured to 40 the channel side thereof and having one flange extending parallel with the adjacent beam-flange and providing a guide groove or space between the two flanges for the engagement of the flanged edge of the next succeeding 45 beam-section, substantially as set forth.

5. In metal sheet-piling, a channel beam-section, and angle-irons rigidly secured to the channel side thereof and having its free flange extending parallel with the beam-flange and 50 providing a longitudinal space therebetween for the engagement of the flanged edge of the next succeeding section in assembling the beams in a wall structure, and the wedge-pieces carried by each section in exerting an 55 inward retaining force from the pressure of the earth walls, substantially as set forth.

In testimony whereof I affix my signature in presence of two witnesses.

LUTHER P. FRIESTEDT.
